SHIPPING OR MAILING CONTAINER

Morton W. Zimmerman, Brooklyn, N. Y.

Application December 12, 1940, Serial No. 369,718

2 Claims.

(Cl. 229—6)

This invention relates generally to packages. More particularly my invention relates to an improved construction for shipping or mailing boxes, cases or packages specifically adapted to carry an envelope or letter along with the shipment of goods.

One of the objects of my invention is to provide a novel shipping or mailing container of the character described which shall be so constructed that an invoice or letter may be readily sent along with the shipment, before or after the container has been packed and which upon arrival at its destination may be easily recognized and readily removed either before or after opening the container.

Another object of my invention is to provide a novel shipping or mailing container of the character described having means whereby a readily accessible invoice envelope or letter may be forwarded with the shipment, which shall be characterized by its simplicity of construction and which will avoid the inconvenience and unpleasan-
tiness of licking or otherwise pasting the adhesive flaps disclosed in the relatively complicated invoice envelope attaching means heretofore employed.

Further objects of my invention will become apparent in the following detailed description thereof.

In the accompanying drawing,

Fig. 1 is a perspective view of a shipping or mailing container constructed in accordance with my invention and having a portion of a wall broken away to disclose the construction thereof;

Figs. 2 and 3 are enlarged cross-sectional views taken substantially on the lines 2—2 and 3—3, respectively, of Fig. 1;

Fig. 4 is a fragmentary perspective view of a shipping or mailing container, similar to Fig. 1, but illustrating a modified form of my invention;

Fig. 5 is a fragmentary perspective view of a shipping or mailing container, similar to Figs. 1 and 4 but illustrating a still further modification of my invention; and

Fig. 6 is an enlarged cross-sectional view taken substantially on the line 6—6 of Fig. 5.

Referring now in detail to the drawing, I have disclosed in Figs. 1, 2 and 3, a shipping or mailing container 10 which I have shown for purposes of illustration to be in the familiar rectangular form of a cardboard packing carton but which, it is understood, may be of any other suitable shape or form.

The container 10 may comprise the usual pairs of side walls 11, end walls 12, bottom wall 14 and

top wall comprising the pairs of inner flaps 15 and outer flaps 16.

As shown, an adhesive strip 17 may be employed along the junction of the free ends of the flaps 15 to seal the package in the customary manner well known to the art.

It is a well known and desirable practice, when shipping merchandise, to send along a bill or invoice with the goods. Many attempts have been made to devise arrangements and constructions to prevent such invoice from being lost, mutilated or overlooked and thereby to eliminate inefficiency and delay caused by having to furnish duplicate invoices. These attempts heretofore made to solve this problem have been expensive due to the fact they were complicated and elaborate.

In accordance with my invention I have provided the following relatively simple and yet efficient construction and arrangement constituting a definite advance in the art.

The walls of the carton 10 may be made of the standard type of construction comprising an inner corrugated cardboard member 20 to which there is adhesively attached an inner sheet of cardboard material 21 and an outer sheet of cardboard material 22.

On any selected wall of the carton 10, such as, for example, one of the outer flaps 15 of the top wall and for a predetermined area, the adhesive, attaching the sheet 22 to the corrugated member 20 is omitted. Such predetermined area between the under-surface of the unattached portion 22a of the sheet 22 and the upper surface of the member 20, designated by the letter A, forms a pocket for and is preferably made large enough to freely accommodate a standard invoice envelope E which it is desired to send along with the shipment.

As shown in Fig. 1 a slit 25 is provided in the outer sheet 22, disposed adjacent one end of said pocket A and communicating therewith.

It is thus seen from the above described construction that an invoice carrying envelope or letter which it is desired to send along with the shipment is merely inserted through the slit 25 into the pocket A. Suitable indicia may be provided on the outer surface of the flap 15 containing the pocket A to call attention to the invoice or letter.

To facilitate the removal of the envelope E from the pocket A, I have provided the corners of the slit 25 with transverse slit portions 25a so that with the finger, or with any suitable instrument one may pry open a corner 25a to tear

away the portion of the layer 22 overlying and forming the top wall of the pocket A to permit the release of the envelope E.

As shown in Figs. 5 and 6, if desired, there may be provided in the free portion 22a of the layer 22 an elongated aperture 25. This aperture 25 is of such size and is so disposed that the address on the invoice envelope in the pocket A will be visible through the opening 25 and thereby dispense with the necessity of marking the carton with the address.

It is seen from the foregoing description that my invention may be satisfactorily worked out in connection with any type of carton, made from any suitable type of material comprising layers or sheets adhesively joined.

It is also noted that the pocket A and the slit 25 communicating therewith, instead of being positioned on a closing flap of the carton or container 10 may be positioned on any other desired wall thereof and that my invention extends to such use.

In Fig. 4 I have shown a modified form of carrying out my basic inventive idea. In this form, instead of forming a pocket by providing a free unattached portion of the uppermost layer of a flap, or wall of the carton 10', I provide a slit 30 running clear through the entire thickness of the flap 15'. In this form of my invention it is merely necessary to insert the invoice envelope or letter E' through the slit 30 to lie between the under-surfaces of the flap 15' and of the flap 16.

If there is no flap 16 then the envelope E' would be held captive between the wall 15' and the goods within the container. If desired, to facilitate the insertion and removal of the envelope E', I provide an additional through slit 31 transverse to the position of the slit 30 and joined thereto at the corner 33. An ordinary pasteur tab 32 may then be placed over the corner 33 to prevent loss of the envelope E' or to prevent access to the ma-

terials inside the carton 10'. In this form of my invention it is noted that an additional slit similar to the slit 30 and parallel thereto may be provided at the free end of the slit 31.

5 In the Figs. 1 to 3 and Figs. 5 and 6 forms of my invention a removable adhesive protective strip 40 may be provided overlying all but one corner of the slit 25 as shown in Fig. 1.

In accordance with the provisions of the patent 10 statutes, I have herein described the principle and operation of my invention, together with the apparatus which I now consider to represent the best embodiment thereof, but I desire to have it understood that the apparatus shown is only 15 illustrative and that the invention can be carried out by other means. Also, while it is designed to use the various features and elements in the combination and relations described, some of these may be altered and others omitted without 20 interfering with the more general results outlined, and the invention extends to such use.

Having described my invention, I claim as new and desire to secure by Letters Patent:

25 1. In a container of the class described a wall comprising a corrugated sheet of material, a flat sheet of material overlying said corrugated sheet and adhesively attached thereto except for a pre-determined area thereof, the portions of said corrugated sheet and said overlying layer in said pre-determined area being free and unattached to 30 form a pocket therebetween for the reception of an invoice envelope or letter and a slit in said overlying layer, communicating with said pocket, said slit being of sufficient size to permit the 35 passage therethrough of said invoice envelope or letter.

2. A container according to claim 1 in which 40 said slit comprises a main portion and an auxiliary portion at an angle thereto for the purposes set forth.

MORTON WM. ZIMMERMAN.
